(57) **CLAIM**

The ornamental design for an inflatable pool, as shown and described.

DESCRIPTION

FIG. 1 is a perspective view of an inflatable pool illustrating my new design, in which the inflatable pool is shown in a deployed condition;

FIG. 2 is a front elevation view thereof, it being understood that a rear elevation view thereof is identical;

FIG. 3 is a left side elevation view thereof, it being understood that the right side elevation view thereof is identical; FIG. 4 is a top plan view thereof;

FIG. 5 is a bottom plan view thereof;

FIG. 6 is a perspective view of another inflatable pool illustrating my new design, in which the inflatable pool is shown in a deployed condition;

FIG. 7 is a front elevation view thereof, it being understood that a rear elevation view thereof is identical;

FIG. 8 is a left side elevation view thereof, it being understood that the right side elevation view thereof is identical; FIG. 9 is a top plan view thereof;

FIG. 10 is a bottom plan view thereof;

FIG. 11 is a perspective view of another inflatable pool illustrating my new design, in which the inflatable pool is shown in a deployed condition;

FIG. 12 is a front elevation view thereof, it being understood that a rear elevation view thereof is identical;

FIG. 13 is a left side elevation view thereof, it being understood that the right side elevation view thereof is identical;

FIG. 14 is a top plan view thereof;

FIG. 15 is a bottom plan view thereof;

FIG. 16 is a perspective view of another inflatable pool illustrating my new design, in which the inflatable pool is shown in a deployed condition;

FIG. 17 is a front elevation view thereof, it being understood that a rear elevation view thereof is identical;

FIG. 18 is a left side elevation view thereof, it being understood that the right side elevation view thereof is identical;

FIG. 19 is a top plan view thereof; and,

FIG. 20 is a bottom plan view thereof.

The broken lines appearing in the several views form no part of the claimed design. Unclaimed subject matter is shown in broken lines for the purpose of illustrating the environment in which the article embodying the design is used.
